[57] CLAIM

The ornamental design for a combined display and dispensing rack for cosmetic products, as shown and described.

DESCRIPTION

FIG. 1 is a front perspective view of a combined display and dispensing rack for cosmetic products showing my new design;

FIG. 2 is a top plan view thereof with the support folded; FIG. 3 is a rear elevational view thereof;

FIG. 4 is a side elevational view thereof, with the opposite side being a mirror image, and wherein the only difference resides in the closure of the holder elements; and, FIG. 5 is a bottom plan view thereof.
